United States Patent Office

Des. 210,538

Patented Mar. 19, 1968

210,538

LOUDSPEAKER

Uolevi L. Lahti, 516 E. Liberty, Ann Arbor, Mich. 48108

Filed Dec. 22, 1966, Ser. No. 5,153

Term of patent 14 years

(Cl. D26—14)

FIG.1

FIG.2

FIG.3

FIG.4

FIGURE 1 is a top plan view in perspective of a loudspeaker according to the invention;

FIGURE 2 is a plan view as seen from above of the loudspeaker of FIGURE 1;

FIGURE 3 is a view in side elevation of the loudspeaker of FIGURE 1;

FIGURE 4 is a view in perspective as seen from below, of the loudspeaker of FIGURE 1.

The stippling in the drawings is provided to indicate shading and contrast in appearance.

I claim:

The ornamental design for a loudspeaker, substantially as shown and described.
